UNITED STATES PATENT OFFICE.

WILLIS F. EPPERSON, OF LADOGA, INDIANA.

GLUING-MACHINE.

SPECIFICATION forming part of Letters Patent No. 738,784, dated September 15, 1903.

Application filed November 28, 1902. Serial No. 133,074. (No model.)

To all whom it may concern:

Be it known that I, WILLIS F. EPPERSON, a citizen of the United States, residing at Ladooga, in the county of Montgomery and State of Indiana, have invented certain new and useful Improvements in Gluing-Machines, of which the following is a specification.

My present invention consists in certain improvements upon the machine shown and described in Letters Patent No. 707,219, issued to me August 19, 1902, whereby the utility and efficiency of such a machine are increased, as will be hereinafter more particularly described and claimed.

Referring to the accompanying drawings, which are made a part hereof, and on which similar reference characters indicate similar parts, Figure 1 is a top or plan view of a machine embodying said invention; Fig. 2, a longitudinal vertical sectional view thereof as seen when looking in the direction indicated by the arrows from the dotted lines 2 2 in Figs. 1, 3, 4, and 5; Figs. 3, 4, and 5, transverse vertical sectional views on the dotted lines 3 3, 4 4, and 5 5, respectively, in Fig. 2; Fig. 6, a detail plan view as seen from the dotted line 6 6 in Fig. 2, and Fig. 7 a detail plan and sectional view as seen from the dotted line 7 7 in Fig. 2.

As best shown by Figs. 2 and 3, the general construction and arrangement of the principal parts of my machine are the same as heretofore and as illustrated in my said Patent No. 707,219, and consist, briefly speaking, of a main body portion containing a receptacle for hot water, steam, and the like, by which the glue is kept in a liquid condition and to which steam or hot-water pipes 10 and 11 are connected, said receptacle being preferably composed of an outer shell 12 and a top 13, the latter of which is also formed to contain a chamber 14 for the glue. The parts 12 and 14 are shown as secured together by bolts 15, and a gasket or packing-strip 16 is interposed for the purpose of making steam and water tight joint. The glue-applying wheel 17 is also constructed and arranged substantially as before, and its journals are mounted in bearings on the top 13 in the same manner.

In the present case, however, the glue-receptacle is continued upwardly past said bearing nearly to the upper portion of said glue-applying wheel by means of a box-like extension 20. This enables the wheel to be almost completely immersed in the hot glue, with the advantage, among others, that the bearings are kept free from cooled or hardened glue, so that the wheel may at all times revolve freely, and the journals thereof being at all times immersed in the hot liquid glue need no lubrication. Mounted on the upper side of this box-like extension is a pan 25, surrounding the same, said pan being arranged to receive and hold any glue which may escape from the wheel while in operation. The central portion 26 of said pan is raised and immediately surrounds the upper edge of the box 20, and the horizontal top part of said central portion comes up near the sides of the glue-applying wheel 17, so that the glue-receptacle, except as to the necessary orifice for said glue-applying wheel, is substantially covered at all times. Secured to said central or top portion alongside the opening for the wheel is a scraper 30, (see especially Fig. 2,) which said scraper as the wheel revolves acts to prevent too great a quantity of glue from being carried up by the wheel to the article to which it is being applied. It is necessary in order to adapt the machine to the various classes of work that this scraper should be adjustable, so that a greater or less quantity of glue may be applied under varying circumstances. In order to accomplish this, I have made the pan carrying the scraper adjustable. A downward extension 27, secured to one end of said pan, has a screw-threaded perforation with which a screw 35 engages, said screw being revolvably but not longitudinally movable, as by having a reduced portion in its shank which fits into a recess formed therefor in a lug 36 on the top 13. The part 27 being secured rigidly to the pan 25, turning the screw 35 will move said pan longitudinally, and thus cause the scraper carried by said pan to approach or recede from the wheel, whereby the desired adjustment is secured. Studs or stops 18 and 19 on the upper surface of the top 13 guide and limit this movement, the part 27 having a bifurcated foot 28, which passes astride the stud 18, while a corre-

sponding bifurcated foot 41 on the part 40 at the other end passes astride the stud 19, as will be presently described.

The pan 25 is removable. It is held in place by the following means: A post or standard 37 extends upwardly from the top 13 at a point to one side of and near to the lug or ear 36, and upon the top of this post or standard is pivotally held a latch-bar 45, preferably by means of a pivot-screw 46, and said latch-bar engages with a catch 47, which is shown as an extension from the upper portion of the part 27. When said latch-bar 45 is swung around over said catch between the same and the bottom of the pan 25, it holds that end of said pan to which it is attached securely in place, as will be readily understood. On the opposite end of the pan is the member 40, which, as before stated, extends down and has a foot 41, which rests on the top 13, and the bifurcated end of which passes out astride the stud 19 and extends nearly to the end of said top 13. A latch-bar 50 is pivoted to the top 13, and when it is swung over the point of the foot 41, as best shown in Figs. 2 and 6, it securely holds that end of the pan to which the structure 40 is attached to the main body of the device, the foot 41 in this arrangement forming a catch. When the latch-bars 45 and 50 are swung back, the pan is free to be removed, as the recess in the lug 36 is open at the top, so that the bolt 35 may lift out freely when the pan is raised.

A funnel-like extension 21 is formed at the rear side of the central portion 26 of the pan 25, which enables the liquid glue to be poured in conveniently from time to time to replenish the supply as may be needed. This, however, necessitates that the guide-bar 60 shall be removable, so that the pan and attached parts can be removed. That this may conveniently be done the horizontal portions of the standards 61, to which said guide-bar is attached, are slotted in their ends, and the bolts 62 therefore need not be removed, but only loosened slightly to permit the guide-bar 60 to be slipped off, as will be readily understood.

Having thus fully described my said invention, what I claim as new, and desire to secure by Letters Patent, is—

1. The combination, in a gluing-machine, of the glue-receptacle having walls extending to above the trunnions of the glue-applying wheel, bearings for said trunnions inside of said walls, a glue-applying wheel revolvably mounted in said receptacle the trunnions whereof rest in said bearings and are adapted to be submerged by the glue in said receptacle, and a pan mounted on said receptacle and forming a cover therefor and provided with a slit through which the upper edge of the glue-applying wheel extends and also adapted to catch the surplus glue as it escapes from the wheel, substantially as set forth.

2. The combination, in a gluing-machine,

of a glue-receptacle, a glue-applying wheel revolvably mounted in said receptacle, said receptacle being provided with sides which extend nearly to the top of said wheel above the journals thereof, and a pan mounted on the top of said receptacle and forming a cover therefor and provided with a slit through which the upper edge of said wheel extends, the portion of said pan adjacent to said wheel being raised above the bottom, and the surrounding portions arranged to form a receptacle for the escaping surplus glue, substantially as set forth. 70 75 80

3. The combination, in a gluing-machine, of a glue-receptacle, a pan mounted thereon and forming a removable cover therefor, a slit in said pan forming an opening through which the upper edge of the glue-applying wheel extends, said glue-applying wheel, and a funnel-like spout attached to said cover portion through which the supply of liquid glue in the receptacle may be replenished without removing the pan or cover, substantially as set forth. 85

4. The combination, in a gluing-machine, of a glue-receptacle the walls whereof extend up around the glue-applying wheel, said glue-applying wheel suitably journaled therein, a cover portion mounted on the top of said receptacle, a scraper edge thereon alongside the edge of said glue-applying wheel which rises as the work progresses, feet secured to the under side of said cover and extending down to the surface of the machine, latches engaging therewith for holding the cover in place, a screw engaging with one of said feet, and a lug on the frame of the machine engaging with said screw, whereby the pan or cover carrying the scraper may be adjusted in respect to the wheel and the quantity of glue to be delivered by the wheel thus regulated, substantially as set forth. 95 100 105

5. The combination, in a gluing-machine, of a body portion comprising the glue-receptacle, a glue-applying wheel revolvably mounted in said glue-receptacle, the sides of said receptacle extending upwardly nearly to the top of said wheel, a removable pan-like cover mounted on said receptacle, catches (as 47 and 41) secured to the under side of said pan, and swinging latches (as 45 and 50) pivoted to the frame or body of the machine and adapted to swing over said catches and thus secure the pan in place, substantially as shown and described. 110 115

6. The combination, in a gluing-machine, of the frame or body, a glue-receptacle therein, a glue-applying wheel revolvably mounted in said receptacle, a pan or cover mounted on said receptacle and provided with downwardly-extending portions terminating in bifurcated feet resting upon the top of the frame or body, said frame or body, being provided with guiding-lugs astride which the bifurcated feet pass, and means for removably securing the pan in place on said frame or body, substantially as set forth. 120 125 130

7. The combination, in a gluing-machine, of the frame or body, a gluing-receptacle therein, a glue-applying wheel revolvably mounted in said receptacle, a removable pan or cover mounted on said receptacle around said wheel, a scraper carried thereby adjacent to said wheel, means for removably securing the pan or cover in place, and other means for adjusting said pan or cover as a whole relatively to said wheel.

8. The combination, in a gluing-machine, of a frame or body embodying a glue-receptacle, a glue-applying wheel revolvably mounted in said receptacle, a cover removably mounted on said receptacle adjacent to said wheel and provided with a scraper edge near the upwardly-moving side thereof, a downwardly-extending part on said cover containing a screw-threaded perforation, a lug on the frame or body, a screw entering said screw-threaded perforation and revolvably and detachably but not longitudinally movable in respect to said lug, whereby adjustment of

said cover is provided for without preventing its removability, substantially as shown and described.

9. The combination, in a gluing-machine, of a frame or body containing a glue-receptacle, a glue-applying wheel revolvably mounted in said receptacle, a removable cover on said receptacle in which a funnel-like spout is secured for the introduction of the liquid glue, a guide-bar mounted above said glue-applying wheel for guiding the material to be glued, said spout being positioned behind said bar and said bar being removable to permit the cover including said spout to be removed when desired, substantially as shown and described.

In witness whereof I have hereunto set my hand and seal at Ladoga, Indiana, this 11th day of November, A. D. 1902.
